UNITED STATES PATENT OFFICE.

WILLIAM F. BOSSERT, OF UTICA, NEW YORK.

APPARATUS FOR OPERATING SWITCH-POINTS.

1,136,767.

Specification of Letters Patent.

Patented Apr. 20, 1915.

Application filed August 27, 1914. Serial No. 358,921.

To all whom it may concern:

Be it known that I, WILLIAM F. BOSSERT, a citizen of the United States, residing at Utica, in the county of Oneida and State of New York, have invented certain new and useful Improvements in Apparatus for Operating Switch-Points; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in adjustable connections for switch points and the object in view is to produce a simple and efficient apparatus of this nature so constructed that the points of a switch may be operated through the medium of suitable switch throwing apparatus, means being provided to allow for the creeping of the rail incident to variations in temperature.

The invention consists more specifically in the provision of adjustable connections for switch points of means whereby snow, ice, cinders or other foreign matter may be effectually prevented from interfering with the adjustment of the parts which are connected to the switch throwing points.

The invention comprises various details of construction, combinations and arrangements of parts which will be hereinafter fully described, shown in the accompanying drawings and then specifically defined in the appended claims.

My invention is illustrated in the accompanying drawings, in which:

Figure 1 is a cross sectional view through the apparatus, parts being shown in elevation. Fig. 2 is a central longitudinal sectional view through the casing in which the adjustable switch operating rods pass. Fig. 3 is a detail view in elevation showing flanged caps forming a part of the invention. Fig. 4 is a cross sectional view centrally through the cap shown in Fig. 3. Fig. 5 is a detail view of a double washer, forming a part of my invention. Fig. 6 is a central cross sectional view through the member shown in Fig. 5. Fig. 7 is a central longitudinal sectional view through the casing showing a slight modification of the apparatus. Fig. 8 is a still different modified

form of a detail of the invention. Fig. 9 is a modified form of cap used in connection with the form shown in Fig. 7. Fig. 10 is a sectional view centrally through the cap shown in Fig. 9. Fig. 11 is an elevation of the form of cap shown in Fig. 8, and Fig. 12 is a sectional view centrally through the modified form of cap shown in Fig. 11.

Reference now being had to the details of the drawings by numeral, 1 designates a casting having a flanged portion 2, apertured for the reception of bolts 3, forming means whereby the switch point throwing bar 4 may be securely held to said casting.

A casing, designated by numeral 5, is hollow and provided with a central contracted portion and each end of the casing is flaring as at 6 forming cup-shaped chambers, the inner surfaces of which are concaved as at 7 and form abutment surfaces. A rod 8, circumferentially threaded, passes through said casing and to this any suitable switch throwing apparatus, not shown, is adapted to be attached, whereby a longitudinal movement may be imparted in one direction or the other to said rod. Cylindrical nuts 9 and 12 are mounted upon said rod and have their inner ends convexed, adapted to conform to and bear against the concaved surfaces 7 in the chambered end of the casing, and the circumferences of the outer ends of said nuts 9 are squared as at 10, affording means to be gripped by a wrench or other tool to turn the same upon the rod for adjustment.

11, 11 designate jam nuts mounted upon the rod and bearing against the outer ends of the nuts 9 and 12 to hold the same from loosening.

Caps, designated by numeral 15, have each an annular shoulder 16^x formed therein and each cap has a laterally extending curved flange 16, in which are formed slits 16', shown clearly in Figs. 3 and 4 of the drawings, and which are provided to form a series of resilient fingers which may conveniently spring over a beading 6^x formed about each end of the casing and serve as means for securely holding the caps in place. Said caps are provided with central openings 17 of larger diameter than the diameter of the nuts 9 and 12 and are adapted to receive the short cylindrical portions 18^x of the washers 18. The marginal edge of each cylindrical portion 18^x has a series of fingers 20 upon one edge thereof

which are bent to engage said shoulders 16^x of the caps, as shown in Fig. 2 of the drawings, thus forming a secure means for holding the washers in place. The diameters of the cylindrical parts of the washers are adapted to fit closely about the circumferences of the nuts 9 and 12.

In Fig. 7 of the drawings, I have shown a slight modification of my invention in which the cap 23, details of which are shown in Figs. 9 and 10, has a cylindrical flange 24 which is adapted to telescope over the end of the casing 6^a and is apertured for the reception of the rivets 25, passing through said flanges and through apertures in the wall of the casing. The end of the casing 6^a has an annular shoulder formed in the inner surface thereof for the reception of a washer 23' and against which washer the cap 23 bears, thus closing the opening intermediate the nut 21 and the inner surface of the chambered portion of the casing. In the form shown in Fig. 7, the jam nut 22 is mounted upon the rod and bears against and is adapted to hold the nut 21 in an adjusted position.

Referring to Fig. 8 of the drawings, I have shown a still different modified form of cap, designated by numeral 26, which has an inwardly extending flange 26^a which telescopes within the casing and is held in place by means of rivets 28, while the outer portion of the cap is bent to form a flange 27 receiving a washer 29, the opening in which fits about the circumference of the nut 21^a, and 22^a designates a jam nut mounted upon the rod and engaging the rod 21^a.

By the provision of the switch point adjusting mechanism described, it will be noted that a lost motion means is provided whereby creeping of the rails incident to variations in temperature is provided for, and, through the medium of the caps and washers, snow, ice, cinders and foreign matter may be effectually prevented from lodging inside the casing and thereby avoiding any interference with the adjustment of the parts.

What I claim to be new is:—

50 1. An apparatus for adjusting switch points on railways comprising a casing to which the switch point throwing bar is adapted to be connected, said casing having chambered ends with concaved abutment walls, a threaded operating rod passing through said casing, cylindrical nuts upon said rod and having their inner ends convexed to conform to said abutment surfaces, and apertured caps fitted to the ends of the casing and about said nuts.

60 2. An apparatus for adjusting switch points on railways comprising a casing to which the switch point throwing bar is adapted to be connected, said casing having chambered ends having concaved abutment

walls, a threaded operating rod passing through said casing, cylindrical nuts upon said rod and having their inner ends convexed to conform to said abutment surfaces, apertured caps fitted to the ends of the casing, about said nuts, a space intervening between the casing and caps, and a washer adapted to close said space. 70

3. An apparatus for adjusting switch points on railways comprising a casing to which the switch point throwing bar is adapted to be connected, said casing having chambered ends having concaved abutment walls, a threaded operating rod passing through said casing, cylindrical nuts upon said rod and having their inner ends convexed to conform to said abutment surfaces, apertured caps fitted to the ends of the casing, and provided with openings of larger diameter than the diameter of the nuts, and washers interposed between the ends of the casing and cap. 80

4. An apparatus for adjusting switch points on railways comprising a casing to which the switch point throwing bar is adapted to be connected, said casing having chambered ends having concaved abutment walls, a threaded operating rod passing through said casing, cylindrical nuts upon said rod and having their inner ends convexed to conform to said abutment surfaces, apertured caps fitted over the ends of the casing, and provided with openings of larger diameter than the diameters of said nuts, washers of larger diameter than the apertures in said caps and having a central opening 90 engaging the circumferences of the nuts. 95

5. An apparatus for adjusting switch points on railways comprising a casing to which the switch point throwing bar is adapted to be connected, said casing having chambered ends having concaved abutment walls, a threaded operating rod passing through said casing, cylindrical nuts upon said rod and having their inner ends convexed to conform to said abutment surfaces, each end of said casing having a beading about its circumference, a cap having a central opening and a laterally extending curved flange which is slotted, forming series 105 of fingers adapted to spring over said beading, and washers mounted one about each nut and interposed between the same and said caps. 110

6. An apparatus for adjusting switch points on railways comprising a casing to which the switch point throwing bar is adapted to be connected, said casing having chambered ends having concaved abutment walls, a threaded operating rod passing through said casing, cylindrical nuts upon said rod and having their inner ends convexed to conform to said abutment surfaces, each end of said casing having a beading about its circumference, a cap having a cen- 120

130

tral opening and a laterally extending curved flange which is slotted, forming series of fingers adapted to spring over said beading, washers, each having a short cylindrical portion adapted to surround a nut and extending through the opening in the cap, the inner end of each washer provided with a series of fingers designed to engage the in-

ner edge of the cap to fasten the same thereto.

In testimony whereof I hereunto affix my signature in presence of two witnesses.

WILLIAM F. BOSSERT.
